UNITED STATES PATENT OFFICE.

JUAN B. URBANO, OF BAGUIO, PHILIPPINE ISLANDS.

ELECTRIC PENCIL.

1,247,038.

Specification of Letters Patent. Patented Nov. 20, 1917.

Application filed June 14, 1917. Serial No. 174,710.

To all whom it may concern:

Be it known that I, JUAN B. URBANO, a citizen of the United States, residing at Baguio, in the Province of Mountain, Philippine Islands, have invented certain new and useful Improvements in Electric Pencils; and I do hereby declare the following to be a full, clear, and exact description of the invention, such as will enable others skilled 10 in the art to which it appertains to make and use the same.

This invention relates to writing implements, and has particular reference to an illuminated pencil.

15 The object of the invention is to provide an improved form of pencil which may be illuminated to facilitate the act of writing in the dark. In connection with this invention, it is furthermore the object to provide an illuminated pencil which may also be utilized as a flash light for general purposes when the writing device is not needed. To this end, the pencil is provided with a protective cap in which is fitted a lens, this 25 protective cap forming of the pencil, a flash light of generally accepted form when in its position of protecting the point of the pencil and the lamp bulb, it being readily removed in order to permit the use of the pencil 30 point.

A further object of the invention is to provide an implement of the above described type having an improved form of switch, in that the switch also constitutes a clip for 35 securing the pencil in the pocket when the device is not in use.

With the above objects in view and such others as may hereinafter appear, my invention will now be fully set forth and described, reference being had to the accompanying drawings:—

In the drawings:—

Figure 1 is a longitudinal section through the entire device with the protective cap 45 inclosing the pencil point,

Fig. 2 is an enlarged sectional view of the forward end of the device with the protective cap removed,

Fig. 3 is an enlarged detail of the rear 50 end of the device showing the protective cap positioned thereon, and

Fig. 4 is a section on line 4—4 of Fig. 1.

Referring more particularly to the drawings 55 1 represents a casing section within which is formed, along one side, the pencil

body 2, and also upon the opposite side, a tubular body 3 which constitutes a portion of the lamp structure. The pencil body 2 may be of any well known formation, and in the present instance is shown as having 60 a longitudinally extending lead receptacle 4 from which a lead body 5 may be projected and clamped within a conical head 6, the latter being threaded within the end of the body 2 so that a slight turn in one direction or the other will permit the release or the tightening of the lead, for purposes of adjustment of the point. The receptacle 3 is provided at its forward end with a lamp socket 7 from which extends a conductive member 8 of leaf metal material which terminates at the stud 9 in electrically connected relation thereto. The stud 9 carries the spring clip 10 whose free end is provided with a head 11 which stands in 70 normally spaced relation to a contact plate 12. The latter is riveted in position upon a rivet or stud 13 whose inner end is connected to a second leaf metal protective strip 14 which extends along the inside of 75 the tubular element 3, and at the end of the section 1 terminates in a foot 15 which is positioned to contact with one of the poles of a battery 16. Extending along the opposite side of the tubular structure 3 is a 80 conductor 17 whose forward end is outwardly turned into a spring contact 18 positioned to receive the central contact of the lamp 19 positioned in the socket 7 and whose rear end is formed into a contact foot 20 which 85 is positioned to bear against the central pole of the battery 16. The battery 16 is carried in a section 21 which is slightly larger in diameter than the section 1 and is centrally threaded at its forward end to be screwed 90 onto the rear end of the section 1. When properly screwed onto the rear end of the section 1, the poles of the battery 16 are brought into proper relation to the contacts 15 and 20. The rear end of the section 21 95 is closed by a suitable plug or cap 22 which is threaded thereon and when screwed up so that the flange 23 bears against the rear edge of the section 21, compresses a coil spring 24 into close contact with the rear 100 end of the battery 16 so that the latter is properly held up in position.

In order to protect the bulb 19 and the pencil point, a cap 25 of sufficiently elongated nature is threaded upon the forward 110

end of the section 1, and has its outer end provided with a lens 26, so that it is not necessary to remove the cap 25 from the forward end of the section 1 in order to permit the 5 light emanating from the bulb 19 to be successfully employed when it is not necessary to use the pencil, but merely to use the device as a flash light. When it is required to use the pencil, the cap 25 may be re- 10 moved and screwed upon threads 27 formed upon the cap 22 behind the flange 23, after the manner of some well known fountain pens, when the pencil may be employed and the light used to illuminate either the writing 15 or for the intermittent use of the pencil and the light. It should be noted that the clip 10 which forms with the plate 12, the switch for energizing the lamp 19 is positioned and formed to provide a securing 20 device whereby the pencil may be secured in the user's pocket, this element 10 thereby having a double function, one of which it is impossible to carry out when the device is fulfilling the other. Thus, 25 when the clip 10 is being used to fasten the device into a coat pocket, it is impossible for the head 11 to come into contact with the plate 12 through accident, with the re-

sult that the energy upon the battery will be consumed without purpose.

From the foregoing it will be apparent that I have provided a very simple and compact form of pencil and illuminating device which has several advantageous features of improvement over other flash lights 30 or pens and pencils of similar types. 35

What I claim as my invention is:—

An illuminated pen comprising in combination, a section including a writing implement structure and a light supporting 40 means at the front end thereof, a switch device, a battery containing section secured upon the rear end of the first mentioned section, a protective cap removably carried by the forward end of the first mentioned 45 section and inclosing the implement and light, and a lens secured in said protective cap to permit the use of the light without the removal of the cap.

In testimony whereof, I affix my signature in the presence of two witnesses.

JUAN B. URBANO.
